CASING FOR A PHOTOCOPY MACHINE OR THE LIKE

Thomas G. Dulin, Penfield, N.Y., assignor to Litton Business Systems, Inc., Orange, N.J., a corporation of New York

Filed Oct. 4, 1967, Ser. No. 8,854

Term of patent 14 years

(Cl. D61—1)

FIG. 2

FIG. 3

FIG. 4

FIG. 1

FIG. 1 is a front view of a casing for a photocopy machine or the like embodying my new design.

FIG. 2 is a left side view thereof.

FIG. 3 is a right side view.

FIG. 4 is a top plan view; and

FIG. 5 is a rear view thereof.

I claim:

The ornamental design for a casing for a photocopy machine or the like, as shown.
